(57) **CLAIM**

The ornamental design for a beverage cooler, substantially as shown.

DESCRIPTION

FIG. 1 is a perspective view showing the front, top and right sides of a beverage cooler embodying our new design;

FIG. 2 is a front elevation view thereof;

FIG. 3 is a right side elevation view thereof, the left side elevation being a mirror image of the right side elevation as shown;

FIG. 4 is a rear elevation view thereof;

FIG. 5 is a top plan view thereof;

FIG. 6 is a bottom plan view thereof; and,

FIG. 7 is a perspective view showing the rear, top and left sides thereof.
